UNITED STATES PATENT OFFICE.

WILLIAM WALTER, OF SALTSBURG, PENNSYLVANIA.

CHURN.

SPECIFICATION forming part of Letters Patent No. 409,533, dated August 20, 1889.

Application filed September 20, 1888. Serial No. 285,911. (No model.)

To all whom it may concern:

Be it known that I, WILLIAM WALTER, a citizen of the United States, and a resident of Saltsburg, in the county of Indiana and State 5 of Pennsylvania, have invented certain new and useful Improvements in Churns; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a representation of this invention and is a top view. Fig. 2 is a vertical section.

The invention relates to improvements in churns; and it consists in the construction 20 and novel combination of parts, as hereinafter set forth.

Referring to the drawings, A designates the churn-body, and B is the cover thereon having the projection C at one side, upon 25 which is secured the bearings a for the crank-shaft D. The object in placing the crank-shaft at the outer end of the projections is to remove the operator from the fumes of the hot water contained in the tub E. The cover 30 B has the lateral lugs b, perforated to engage the rods c c', rising from and secured to the churn-body. One of said rods c' is longer than the other, so that the cover may be lifted upward and swung to one side, carrying the 35 dasher out of and resting its lower end on the edge of the churn-body when it is desired to remove the butter and wash the churn.

F designates the dasher-blades, perforated in the usual manner and radiating from the 40 vertical shaft G, which extends upward through openings in the cover and frame H, and has the pinion d secured thereon.

I is the rack-bar engaging the pinion d, and having its opposite side moving in the 45 overlapping guide-plate e, secured to the frame H, and a pin f, standing from said frame, projects through a central longitudinal

slot g in the plate. The rack-plate is reciprocated by means of the pitman-connection J with the crank of the shaft D. It is obvious 50 that the reciprocation of the rack-plate will convey a vibratory motion to the dasher-blades within the churn-body.

The hot-water tub E has secured to its bottom the brackets K, designed to hold the 55 churn-body free from the bottom of the tub to allow water to cover or surround the churn. The integral spring-arms L, standing upward from the brackets K, are designed to embrace the churn-body and prevent lateral 60 movement.

The churn is securely fastened within the tub by means of hooks h and eyes i, secured, respectively, to the tub and churn-body.

Having described my invention, what I 65 claim is—

1. The combination, with the churn-body having the long rod c' and the short rod c, of the cover having the projection and the perforated lugs, said long rod being adapted to 70 permit of the movement thereon of said cover with the dasher while the dasher is being removed, and to permit the dasher to remain connected to the churn-body after such removal, substantially as set forth. 75

2. In a churn, the combination, with the churn-body having the long rod c' and short rod c, and the cover having the projection and the perforated lugs, of the crank-shaft having bearings extending from the cover 80 projection, the rack-plate, the overlapping guide-plate, the pitman, and the dasher-shaft having the pinion, substantially as specified.

3. In a churn, the combination, with the churn having the eyes and the tub having 85 the hooks, of the brackets secured to the bottom of said tub, provided with the spring-arms, substantially as specified.

In testimony whereof I affix my signature in presence of two witnesses.

WILLIAM WALTER.

Witnesses:

A. O. WALTER,
W. T. CLINE.
